mesne assignments, to American Optical Com-
pany, Southbridge, Mass., a voluntary associa-
tion

Application August 14, 1942, Serial No. 454,867

16 Claims. (Cl. 51—65)

1

This invention relates to honing or stropping machines and has particular reference to a new and improved apparatus for honing and stropping blades for microtones and the like.

An object of the invention is to provide an apparatus for automatically honing and stropping blades for microtones or the like.

Another object of the invention is to provide an apparatus for the type set forth having means for oscillating the blade during the honing or stropping thereof.

Another object of the invention is to provide an apparatus of the type set forth with means for automatically lubricating the honing plate during the honing operation.

Another object of the invention is to provide an apparatus of the type set forth with means for automatically shortening the stroke during the honing or stropping operation.

Another object of the invention is to provide a new and improved apparatus for controlling the movement of the blade during the honing or stropping thereof.

Another object of the invention is to provide a new and improved means for controlling the movement of the honing plate or strop.

Other objects and advantages of the invention will be apparent from the following description taken in connection with the accompanying drawings. It will be understood that many changes may be made in the details of construction and arrangement of parts without departing from the spirit of the invention as expressed in the accompanying claims. I therefore do not wish to be limited to the exact details of construction and arrangement of parts shown and described as the preferred form has been shown by way of illustration only.

Referring to the drawings:

Fig. 1 is a side view of an apparatus embodying the invention, partly in section.

Fig. 2 is a top or plan view thereof, with the honing stone removed.

Fig. 3 is a fragmentary view showing the tripping mechanism for actuating the controls.

Fig. 4 is a sectional view taken on line 4—4 of Fig. 2 looking in the direction of the arrows.

Fig. 5 is a fragmentary view of the supporting mechanism for the honing plate.

Fig. 6 is a diagrammatic illustration showing the positions assumed by the blade.

Fig. 7 is a fragmentary sectional view taken on line 7—7 of Fig. 2 looking in the direction of the arrows.

Fig. 8 is a view taken on line 8—8 of Fig. 9

2

looking in the direction of the arrows and showing the blade oscillating arrangement.

Fig. 9 is a view partially in section of the blade supporting and oscillating arrangement, taken on line 9—9 of Fig. 2.

Fig. 10 is a view taken on line 10—10 of Fig. 8 looking in the direction of the arrows.

Fig. 11 is an end view on an enlarged scale showing the arrangement for control of the blade support.

Fig. 12 is a sectional view taken on line 12—12 of Fig. 11 looking in the direction of the arrows and

Fig. 13 is a sectional view taken on line 13—13 of Fig. 11 looking in the direction of the arrows.

The apparatus shown embodying the invention comprises an hydraulic source 1 and frame 2. The frame 2 is adapted to be supported on a table or the like 3 and the hydraulic source is adapted to be placed thereunder.

The hydraulic source 1 is provided with the motor 4 adapted to drive the pump 70 to provide power to the hydraulic system.

The frame 2 is provided with the marginal tracks 5 and 6 adjacent the opposite longitudinal edges thereof and in said tracks 5 and 6 are positioned the rollers 7 adapted to support a carriage 8. The carriage 8 is adapted to be moved longitudinally by means of the hydraulic cylinder 9 containing a piston adapted to cause movement of said carriage 8 on said tracks 5 and 6.

The carriage 8 is provided with means adjacent the end thereof for supporting the honing plate support 10. The means on said carriage 8 for supporting the honing blade support 10 consist of screws 11 having elevating knobs 12 and having a member 13 adapted to support the pivot balance 14 on either end of said member 10.

The member 10 is adapted to receive on its upper face a strop or honing member, such as a glass plate or a rubber strap depending on the use to which the machine is to be put.

When the glass plate or the like is used the channels 16 adjacent the opposite ends of said support 10 are filled with water for use in lubricating the surface as hereinafter described.

On the frame and adjacent the center thereof is supported the blade 17 to be honed or stropped by means of the supports 18 and 19 on opposite sides of the frame. These supports are adapted to support the rods 20, 21 and 22 and on the rods 20 and 22 are supported the bearing members 23 and 24. These bearing members 23 and 24 are adapted to act as bearing members for the rod 21 which supports the blade and pivots or

55

revolves the same to proper angular relation with the plate 15. Also adjacent one end of said rods 20 and 22 is supported the arrangement for oscillating the blade during the stropping or honing thereof. This arrangement consists of an electric motor 25 having the eccentric disc 26 secured to the shaft thereof and adapted to engage the collar 27 on the shaft 21. Between the collar 27 and the support 18 is positioned the coil spring or the like 28 adapted to retain said collar in engagement with the eccentric disc 26. It will be seen that on rotation of the eccentric disc 26 that because of said eccentric disc and the spring 28 the oscillating motion will be given to the blade 17.

As the rod 21 is secured to only one side of the blade the opposite side is provided with the rod 29 adapted to engage the opposite side of said blade and support the same during the honing or stropping thereof.

From Figs. 9 and 12 it will be seen that the rod 29 telescopes in the tubular shaft 30 and is adapted to be supported in telescopic relation in the support 24 and said support 24 may be adjusted along rods 20 and 22 and held in place by means of the set screw 31 in the supporting member 24.

On the shaft 29 is provided the driving collar 32 and also the driven collar 33 with the pins 34 from the driving collar 32 extending through openings in the driven collar 33 and having the coil springs 35 positioned thereon between the driven and driving collars. It will thus be seen that because of the springs 35 and oscillating apparatus described above, that it is possible to oscillate the blade 17 during the honing or stropping thereof.

The screw or the like 36 allows the driven collar 33 to be adjusted on the shaft 29 in order that the machine may accommodate blades of varying lengths.

To remove or insert a blade, the rod 21 is retracted by means of the knob 76 and the blade removed and when a blade is inserted the rod 21 is returned to its normal position by the action of the spring 28.

It is pointed out that the blades have openings in the opposite ends thereof which are adapted to receive a pin on the end of the rod 21 and a driving connection or clutch on the end of rod 29. The set screw 77 allows adjustment of rod 21 and its component support 23 to be adjusted so as to position the various lengths of blades on the center of plate 15. The corresponding rod 29 and its support 24 may be adjusted likewise.

It is pointed out that this centering of the blade 17 on the plate 15 gives the advantage that the pressure of said honing plate 15 along the edge of the blade is equalized along the full length of the blade because of the pivotal supports 14 for the carriage 10.

In order that the blade 17 be pivoted or rotated to desired relation with the plate 15, I provide the automatic blade pivoting mechanism 37.

It is pointed out that the angle between the blade and the plate 15 can be adjusted by adjustment of the knob 12 on the screw 11 while retaining the position of the blade 17. This adjustment is necessary because of the variation in blade width and the necessity of having the included angle of the cut tip of the blade at a certain predetermined figure; and because of the necessity that the angle be of such predetermined amount and variation it is necessary that the

plate 15 be adjustable vertically with respect to the pivot axis of the knife to allow the placing of the blade at such predetermined angle with the plate. If desired a protractor scale could be placed on either the blade holder or the frame and a cooperative pointer placed on the other of said members to indicate the angle of position at which the blade is set with respect to the plate 15. This protractor while not absolutely essential is of considerable convenience.

It is further pointed out that in Figs. 1 and 4 a pressure regulator is shown which may be adjusted by adjusting the screw 38 of said pressure regulator to vary the balance of pressure in the hydraulic system as desired.

It is also pointed out that because the blade for which the present device is intended to be used in sharpening is for cutting microscopically thin specimens that the said blades must be more accurately sharpened. For this purpose the apparatus is so constructed that the sharpening plate may be given continued strokes the full length of the apparatus or if desired may be set so as to progressively shorten the strokes of the sharpening plate. For this purpose the trip stops 39 and 40 are provided. The trip stop 40 is fixed and the trip stop 39 travels along the rods 41 and 42. It is pointed out that the trip stop 39 is actually a tripping finger and has the projecting portions 43 and 44 adapted to frictionally engage the upper edges of the rods 41 and 42 respectively, said fingers 43 and 44 act somewhat in the nature of ratchets so that a slight axial movement of the rod 41 causes the moveable trip stop 39 to move along the rod 42. The amount of such movement is controlled by adjustment of the adjusting screw 73 which adjusting screw is adapted to engage the end of the rod 41 to adjust the limit of strokes thereof as described above and in order to progressively shorten the cycle of strokes of said sharpening blade 15. The length of strokes of the machine is determined by the distance between the two trip stops 39 and 40 which distance progressively decreases a given amount each cycle as the rod 41 engages the adjusting screw 73 at the end of each cycle. Stop 39 climbs along the rod 42 toward the stop 40 on each stroke of said rod. The ratchet like fingers 43 and 44 raise off of the rods 41 and 42 by a cross pin that is operated by knob 45 thus by bearing on the knob 45 the movable tripping stop 39 can be released and returned to starting position.

The tripping stops 39 and 40 operating on the pins 47 and 48 actuate the four way valve 46 by means of two corresponding pins 49 and 50. The hydraulic fluid that is delivered by the pump and passes through the starting valve 51 is metered by the four-way valve 46 into either of the two sides of the flipping mechanism hereinafter described. On the forward stroke of the carriage the tripping stop 39 engages the pin 47 which in turn causes the pin 50 to reverse the four-way valve 46 causing the carriage to return. On the return stroke of the carriage the trip stop 40 engages the pin 48 which action causes the pin 49 to return the four-way valve to the starting position.

For certain applications and adaptations of the apparatus it may be desired to place in the volume regulator 52 and the pressure indicator 53 but these are not essential to the operation of the apparatus. These are of the type usually employed in hydraulic systems.

The automatic blade pivoting mechanism 37

has the two ports 54 and 55 which function alternately as intake and exhaust for the supply of hydraulic fluid to the blade pivoting mechanism.

The hydraulic system shown is a low pressure hydraulic system employing standard four-way valve.

In the flipping mechanism is a disc valve 56 operated by the flipping mechanism in which valve are the ports 65, 74 and 75 which act alternately in conjunction with adjacent openings that lead to ports 57 and 58 which ports 57 and 58 act both as intake and exhaust for the main cylinder 9 alternately. Referring to the Fig. 11, fluid entering the port 55 drives the vane 59 in a counter-clockwise direction exhausting the fluid on the opposite side of the vane through the port 54. As the vane 59 closes off the port 54 towards the end of its stroke a cushion action occurs and a flow of a more slower nature occurs through the meter valve 60. In this position of the vane the disc valve permits fluid to flow from port 55 through the inside chamber of the vane and through the port 57, thus actuating the cylinder. During the consequent stroke of the cylinder port 58 acts as a return line. The bleeder valve 61 acts to set the volume of pressure across the vane so as to vary the torque force on the vane and as a result the blade pressure on the hone. This bleeder valve 61 may be adjusted by adjustment of the said screw 62 to vary the amount of fluid allowed to pass therethrough.

When the carriage has reached the extent of its travel in one direction and the tripping mechanism has reversed the direction of movement of the carriage the flow of fluid is reversed so that the port 54 acts as a supply line and the port 55 as the exhaust line. As the reversed fluid enters the port 54 it is prohibited from returning through the cylinder through the port 58 by means of the check valve 65. If this check valve 65 were not employed the carriage would reverse its direction before the flipping mechanism will have reversed its flipping position. This check valve 65 forces the main volume of fluid to return into the chamber 63 by way of the bleeder valve 60 and line 64. The rotational velocity of the vane is brought to its normal height as soon as the vane clears the port 54 on the beginning of its return stroke. As the vane 59 reaches the end of its stroke, opposite that shown in Fig. 11, one opening 74 in the disc valve 56 aligns with the passage to the port 58, while at the same time the reversing valve 46 changes port 54 from a supply line to the exhaust line. Due to this change the end of the cylinder 9 in communication with the port 58 is connected to exhaust and thus prepared for the return stroke, although the return stroke is started slowly due to the above mentioned metering action of valve 60 (on the right side of Fig. 11). The vane 59 meantime covers the ports 57 and 55, and up until the time of reversal of valve 46 the cylinder 9 can exhaust by way of port 57 and through check valve 65 to port 55 and so back to the sump. But as soon as reversal takes place, the check valve stops communication between port 55 and port 57 and pressure fluid is fed to the cylinder 9 only through the metering valve 60.

It is pointed out that with the blade pivoted mechanically as described above, that the actual rotation of the blade and disc valve occur rapidly but that when the greater part of this pivot has taken place the pivoting of the blade then becomes slower when the blade has reached the extent of its pivoting position. Thus the blade

slows down before it strikes the hone so as not to damage the delicate blade.

The secondary action of this flipping mechanism is to vary the pressure on the tip to any desired amount. This is accomplished by the bleeder valve 61 controlled by the said screw 62 which may be adjusted to vary said blade pressure at will.

From the foregoing, it will be seen that I have provided simple, efficient and economical means for obtaining all of the objects and advantages of the invention.

Having described my invention, I claim:

1. Apparatus for sharpening a blade comprising a reciprocable sharpening member, a cylinder and piston for reciprocating said member, fluid actuated means for supporting and flipping a blade in operative relation to said sharpening member on each successive stroke thereof, and a reversing valve operable on successive movements of the sharpening member for reversing the supply of actuating fluid both to said cylinder and to said blade flipping means.

2. Apparatus for sharpening a blade comprising a reciprocable sharpening member, fluid actuated reversible means for reciprocating said member, means independent of the first means for supporting a blade to be sharpened and alternately presenting the opposite sides of the blade to the sharpening member on each successive stroke of said member including a reversible fluid operated motor, and a reversing valve for reversing the supply of actuating fluid both to said reciprocating means and to said reversible motor.

3. Apparatus for sharpening a blade as set forth in claim 2 in which a metering valve in the supply of actuating fluid to the reciprocating means delays movement of the sharpening member until reversal of the blade has been initiated.

4. Apparatus for sharpening a blade comprising a sharpening member having a plane surface for engaging the work, a longitudinally reciprocable support carrying said sharpening member with the direction of reciprocation parallel to said plane surface, fluid actuated means for reciprocating said support and fluid actuated means for supporting and flipping a blade in operative relation to said surface of the sharpening member on each successive stroke thereof, and a hydraulic system for supplying actuating fluid to both said fluid actuated means and to actuate the second mentioned means to press the respective sides of the blade against the surface of the sharpening member during reciprocation of the latter.

5. Apparatus for sharpening a blade comprising a flat sharpening member, means for reciprocating said member with a direction parallel to its sharpening surface, means pivotally supporting a blade adjacent said surface, a fluid pressure actuated servo-motor operatively connected to the blade support for alternately presenting opposite sides of the blade to said surface, and adjustable valve means associated with said motor to vary the torque force exerted by the fluid pressure motor for controlling the blade pressure on said sharpening surface.

6. In a device of the character described, a sharpening member, means for reciprocating said member for sharpening a blade, means for retaining a blade in operative position relative to said sharpening member, said sharpening member having a central sharpening portion and reservoir portions adjacent the opposite ends of said sharpening member, said reservoir portions being

adapted to contain a lubricating medium for the sharpening member, and inclined portions extending from said reservoir portions to said sharpening member for directing flow of the lubricating solution onto the surface of the sharpening member upon reciprocation thereof.

7. In a device of the character described, a sharpening member, means for reciprocating said member for sharpening a blade, means for retaining a blade in operative position relative to said sharpening member, said sharpening member having a central sharpening portion and reservoir portions adjacent the opposite ends thereof for supplying a lubricating solution to the surface of said sharpening member, said reservoir portions being connected to said sharpening surface by inclined runways for facilitating the flow of the lubricating solution for said reservoir portions to and across said sharpening surface upon reciprocation thereof.

8. In a device of the character described, a support, a longitudinally moveable sharpening member on said support, a blade holder for supporting a blade in operative position relative to said sharpening member, means for rotatably presenting the opposite sides of the edge of said blade to the surface of said sharpening member alternately, said blade presenting means comprising a fluid system and a control member for said fluid system, said control member having means for slowing up the speed of movement of said blade as the blade approaches the sharpening member and means for changing the direction of rotation of said blade.

9. In a device of the character described, a support, a sharpening member longitudinally movable on said support, means for longitudinally moving said sharpening member relative to said support, means for supporting a blade in operative position relative to said sharpening member and means actuated by the longitudinal movement of said sharpening member to alternately present the opposite sides of the edge of the blade to said sharpening member and means actuated by movement of said sharpening member for successively shortening the length of each successive longitudinal stroke of said sharpening member during the sharpening of the blade.

10. In a device of the character described, a longitudinally movable sharpening member, means for supporting a blade in position relative to said sharpening member and adapted to present the opposite sides of the edge of the blade alternately to said sharpening member, means for moving said sharpening member relative to said blade support, said means for supporting the blade being actuated by movement of the sharpening member to alternately present the opposite sides of the blade to said sharpening member on each successive stroke thereof, and a motor and cam means for reciprocating the blade during the sharpening thereof.

11. In a device of the character described, a longitudinally movable sharpening member, means for supporting a blade in operative position relative to said sharpening member and means for presenting the opposite sides of the edge of the blade alternately to said sharpening member, means for moving said sharpening member relative to said blade, said means for presenting the

opposite sides of the edge of the blade to said sharpening member comprising a valve member having a control member with said control member being actuated by each successive movement of said sharpening member.

12. In a device of the character described, a movable sharpening member for sharpening a blade, a blade holding member for supporting a blade in operative position relative to said sharpening member whereby said blade will be sharpened by engagement with said sharpening member, means for causing successive strokes in opposite directions of said sharpening member relative to said blade and means operated by said successive strokes of said sharpening member for effecting successively shorter strokes of said sharpening member during the sharpening of the blade.

13. In a device of the character described, a longitudinally movable sharpening member for sharpening a blade, means for supporting a blade to be sharpened in operative position relative to said sharpening member, said central sharpening member having a sharpening portion and reservoir portions adjacent the opposite ends thereof and supported thereby and movable therewith whereby when said sharpening member reaches the end of each stroke a flow of the fluid carried in said reservoir portions from said reservoir portions onto the surface of said sharpening member will be effected to lubricate said surface and also any particles thereon will be washed off.

14. In a device of the character described, a support, a sharpening member mounted on said support for longitudinal movement thereon for sharpening a blade, means for supporting a blade in operative position relative to said sharpening member, a rotatable eccentric member engaging said blade supporting means for effecting reciprocating movement of said blade support and blade during the sharpening of said blade by said sharpening member.

15. In a device of the character described, a support, a longitudinally moveable sharpening member on said support, a blade holder for supporting a blade in operative position relative to said sharpening member, means for presenting the opposite sides of the edge of said blade to the surface of said sharpening member alternately, said blade presenting means comprising a fluid system and a control member therefor and said control member having means for slowing up the speed of movement of said blade as the blade approaches the sharpening member.

16. Apparatus for sharpening a blade comprising a frame having opposed longitudinal guideways, a support reciprocable in opposite directions along said guideways, a sharpening member carried on said reciprocable support by adjustment screws, said screws being arranged at opposite ends of the sharpening member and operable to cant one end of said member relative to the other, a pivotally mounted blade support for engaging an end of a blade to be sharpened, a flipping mechanism splined to said blade support for alternately presenting opposite sides of a blade to the sharpening member, and means for oscillating a blade on said support relative to said flipping mechanism.

ALBIN A. GRADISAR.
